UNITED STATES PATENT OFFICE.

RICHARD WALTON TULLY, OF SIERRA MADRE, CALIFORNIA.

STAGE-SETTING.

1,281,719.

Specification of Letters Patent. Patented Oct. 15, 1918.

Application filed February 6, 1918. Serial No. 215,572.

To all whom it may concern:

Be it known that I, RICHARD WALTON TULLY, a citizen of the United States, and a resident of Sierra Madre, in the county of Los Angeles and State of California, have invented a new and Improved Stage-Setting, of which the following is a full, clear, and exact description.

The object of the invention is to provide a new and improved stage setting arranged to enable an actor to successively appear in two different rôles and without the audience realizing when a desired change is effected.

In order to produce the desired result, use is made of a hollow structure representing a hedge, wall or similar device, and set transversely of the stage approximately at the middle thereof, the structure having a passage sidewise therethrough to provide a front hiding portion in the said structure and a rear entrance portion therein, the hiding portion opening into the said passage to enable an actor to pass from the stage into the said hiding portion to hide therein, the rear entrance portion leading from the back of the stage and being provided with doors opening into the passage to enable another actor to pass from the rear of the stage through the said entrance portion and through the doors into the passage and onto the stage to one side of the structure.

A practical embodiment of the invention is represented in the accompanying drawings forming a part of this specification, in which similar characters of reference indicate corresponding parts in both views.

Figure 1 is a sectional plan view of the stage setting on the line 1—1 of Fig. 2; and

Fig. 2 is an enlarged perspective view of the hollow structure.

As shown in Fig. 1, the stage 10 is provided at the front with the usual footlights 11, at the rear with a rear set piece 12, at one side with wings 13 and at the other side with a set piece 14 adjoining the rear set piece 12 and being provided with a door or a gate 15. Adjacent the side set piece 14 is arranged a kiosk or a similar device 16. A hollow structure 20 representing a hedge, wall or similar device, is set on the stage and extends from the rear set piece 12 forwardly with the front closed end 21 a distance from the footlights 11 to permit persons to pass in front of the structure 20 from one side of the stage to the other. As shown, the structure 20 is arranged intermediate the wings 13 and the

side set piece 14, and the structure is provided with a passage 22 leading from one side of the stage to the other, the passage being preferably in the form of an archway, 60 as indicated in Fig. 2. The portion 23 of the structure 20 in front of the passage 22 is open to the passage 22 and forms a hiding place for an actor passing from one side of the stage into the passage 22 and into the front hiding hollow portion 23. The rear portion 24 of the hollow structure 20 forms an entrance and its rear end 25 opens to the back of the stage through the set piece 12. The front end of this entrance portion 25 70 opens into the passage 22 and is provided with normally closed doors 26. Thus while one actor passes, say, from the front of the stage, in full view of the audience, through the gate 15 to the rear of the set piece 12 and into the hollow entrance portion 25 another actor had previously passed through the gate 15 to the kiosk 16 and from the latter to the passage 22 into the hiding portion 23 at the time the first actor reached the doors 26 and passes through the same to the other side of the stage. Thus while one actor moves into the hiding portion 23 the other actor simultaneously passes from the entrance portion 25 through the doors 26 80 into the passageway and onto the stage without the audience realizing that it is not the same person that started from the kiosk 16 to pass through the passage 22 to the other side of the stage. To the audience the first 90 actor who passed out through the gate 15 has disappeared entirely while the other actor is supposed to pass from the kiosk 16 to the passage 22 to the other side of the stage, but, in fact, he does not pass entirely through the passage but passes into the hiding portion 23 while at the same time the first actor passes through the doors 26 to the right hand side of the stage and simulates the second actor. This stage setting enables 100 an actor to successfully appear in two different roles and without the audience realizing how the change is effected.

The stage setting shown and described has been successfully employed in the performance of the well known play "The Masquerader."

Having thus described my invention, I claim as new and desire to secure by Letters Patent:—

1. In a stage setting, a hollow structure set transversely of the stage approximately

at the middle thereof and having a passage therethrough to provide a front hiding portion and a rear entrance portion, the hiding portion opening into the passage to enable an actor to pass from the stage into the front hiding portion and hide therein, the rear entrance portion leading from the back of the stage and being provided with doors opening into the passage to enable another actor to pass from the rear of the stage through the rear entrance portion and through the doors into the passage and onto the stage.

2. In a stage setting, a rear set piece and a hollow structure set approximately at a right angle to the said rear set piece and terminating at its closed front a distance from the front end of the stage, the said structure having a passage therethrough to divide the structure into a front hiding portion and a rear thoroughfare, of which the hiding portion opens into the passage to allow an actor to pass from the stage by way of the passage into the hiding portion, the thoroughfare opening at its rear to the back of the said

rear set piece and having doors leading to the passage to enable another actor to pass from the rear of the said rear set piece through the thoroughfare into and through the latter onto the stage.

3. In a stage setting, a rear set piece, a side set piece having a gate and joining the said rear set piece, and a hollow structure extending from the rear set piece forwardly and terminating at its front closed end a distance from the front of the stage, the said hollow structure having a passage sidewise therethrough to allow persons to pass from one side of the stage to the other side thereof, the portion of the said structure in front of the said passage opening into the latter and the portion of the said structure in the rear of the passage opening through the said rear set piece to the back of the stage, the front end of the said rear portion opening into the passage and being provided with doors normally closed.

RICHARD WALTON TULLY.
